UNITED STATES PATENT OFFICE

2,670,487

PRESSER PLATE LATCH FOR SELF-WRINKING MOPS

Philip K. O'Connor, Chicago, Ill., assignor to
O-Cedar Corp'n, Chicago, Ill., a corporation of
Illinois

Application November 8, 1950, Serial No. 194,665

6 Claims. (Cl. 15—119)

1

My invention relates to a latch for wringing plates of self-wringing mops. More particularly my invention relates to a fastener for locking a presser plate of self-wringing mops in a raised position. My invention has particular utility in connection with a mop having a presser plate hingedly connected to a sponge-equipped mop-head plate, wherein the presser plate is used for wringing the sponge by rotating it downwardly from a normally raised position.

Self-wringing mops having a mop body composed of an absorbent sponge are in widespread use. Many of these mops have a plate hingedly connected to the front or rear edge of an elongated mop-head plate so that this plate can be folded downwardly and around the sponge to wring it. In these mops the wringing plate is generally equipped with a handle or other means for applying pressure to the plate, and this handle is generally adapted to lie adjacent to the mop handle when the wringing plate is in its normally elevated position. A mop of this type, which has achieved commercial importance because of its rear wringing feature, is illustrated in U. S. Patent No. 2,515,403 issued to N. B. Greenleaf et al.

Considerable difficulty has been experienced in providing a suitable latching means for securing the presser plates of self-wringing mops in a raised or other position in which the presser plate will not interfere with the mopping operation. Where, as in the Greenleaf type of mop, a wringing lever projects upwardly from the presser plate, this lever has been fastened to the mop handle by means of a notched clip arm secured to the handle and engaging a recess in the squeezing lever. This type of fastener has proved unsatisfactory because it must be composed of a high grade of spring steel and must be formed and positioned to very close tolerances. Moreover, it has been found that this type of fastener does not stand up well with continued use, and sometimes breaks off. Therefore, a new type of latching device has been diligently sought, especially for use in conjunction with the Greenleaf type of mop.

It is therefore an object of my invention to devise a means for latching the wringing plate of self-wringing mops which is simple and economical in construction. More specifically it is an object of my invention to devise a fastener for mop presser plates which can be formed from an inexpensive type of steel, and which does not have to be formed to precise dimensions or exactly positioned. It is a further object of my invention to devise a latch to be used in conjunction with the Greenleaf type of mop, which

2

will achieve a simple and cooperative relationship therewith. It is a still further object of my invention to devise a presser plate latch which will hold the presser plate in an upright position without allowing the presser plate or squeezing lever attached thereto to clatter against the mop handle.

I have discovered that the above objects can be substantially accomplished by providing a tongue or flange projecting from the mop-head plate and having an upwardly inclined or arcuate end portion attached to frictionally engage the hinged edge of the wringing or presser plate and thereby latch the wringing plate. I have further discovered that my new fastening means uniquely cooperates with the parts of a mop of the Greenleaf type in which the presser plate is hinged at the rear edge and there is a spring secured centrally around the hinge pin and between the integrally formed hinge barrels. I have further discovered that when the presser plate is provided with an upwardly extending squeezing lever that it is desirable to secure this lever in an upright position but at a small distance from the mop handle to prevent clattering of the lever against the handle. And I have also discovered that my new latch may be readily adapted to accomplish this result.

My invention is illustrated in a specific embodiment in the accompanying drawing, in which—

Figure 1 is a perspective view of a mop of the Greenleaf type having a presser plate hingedly connected to the rear edge and equipped with my new latch; Fig. 2, a fragmentary perspective view of the mop of Fig. 1 with the presser plate in wringing position and showing my latching device disengaged; Fig. 3, an enlarged side sectional view taken in elevation through the center of the mop in Fig. 1 and showing the details of my new latch; Fig. 4 is an enlarged detail view of the latch shown in Fig. 3 and shown schematically in a partially engaged position but with the spring removed; Fig. 5, an enlarged perspective view of the mop sponge equipped with fastening means; Fig. 6, a detail view of my latch showing modifications in the tongue and presser plate edge; and Fig. 7, an enlarged perspective view of a central portion of the mop-head plate showing another modification of the tongue of my latch.

Figure 1 shows a self-wringing mop of the Greenleaf type in conjunction with which I prefer to use my new latch, and with which my latching device has a special cooperation and utility. It will be understood, however, that my latching

device is also advantageous when used with a self-wringing mop which has the presser plate hinged to the front edge of the mop, or otherwise secured in the same relative position. Therefore, I wish it to be clearly understood that in the subsequent description of my invention in combination with the Greenleaf mop, I do not intend to limit the use of my device to such a mop.

With particular reference to Figure 1, the mop shown in the drawings has a handle 1 threadedly received within socket 2. Socket 2 has flange portions 3 projecting laterally at the bottom thereof to provide a means for securing socket 2 to mop-head plate 4. In the illustration given, flanges 3 are secured to mop-head plate 4 by means of spot welds 5.

Sponge 6 is preferably detachably secured beneath plate 4. One method of equipping sponge 6 so that it may be detachably secured to plate 4 is illustrated in Figure 5. A metal backing plate 7 having screws 8 secured therein and projecting upwardly therefrom is glued to the top surface of sponge 6. To further secure backing plate 7, canvas strip 9 is glued onto the top of sponge 6 and over backing plate 7. If desired, backing plate 7 may have raised screw sockets 10 to receive the heads of screws 8.

Mop-head plate 4 preferably has a raised rectangular portion 11 attached to receive backing plate 7. Apertures are provided in mop-head plate 4 to receive screws 8. Wing nuts 12 can be advantageously used to secure screws 8 in mop-head plate 4, as shown in Figure 1.

The structure thus far described provides a complete mop except for the wringing means. This means will now be described in detail, since it is in conjunction with such means that my latching device finds its greatest utility.

In the illustration given, a wringing or presser plate 13 is secured to the rear edge of mop-head plate 4 by means of hinge 14. Hinge 14 preferably has its hinge barrels integrally formed respectively with mop-head plate 4 and presser plate 13. Hinge rod 15 is provided to secure the hinge barrels together and thereby form hinge 14.

Presser plate 13 is provided with squeezing lever 16, which is attached centrally to presser plate 13 and projects laterally therefrom. Squeezing lever 16 can be secured to backing plate 13 by means of spot welding or other means of forming a rigid attachment. The purpose of squeezing lever 16 is to serve as a handle for rotating plate 13 about pin 15 to bring plate 13 to the position shown in Figure 2. When this position is reached, sponge 6 can be wrung by applying pressure to lever 16 while holding handle 1.

While mopping, it is necessary that plate 13 be held in a raised position so that it will not strike the surface being mopped. It is desirable, in fact, to secure presser plate 13 in a substantially upright position above plate 4, and to have lever 16 aligned with handle 1. However, to accomplish this a latch or fastener must be provided. The fastener of my invention will now be described.

Looking first at Figure 7, it can be seen that I provide a flange or tongue 17 which projects laterally from mop-head plate 4. Tongue 17, as shown in Figure 7, has an end portion 18 which is inclined upwardly and has an arcuate shape.

Although tongue 17 can be separately formed and then secured to the top of plate 4, I prefer that tongue 17 be integrally formed with plate 75

4, as seen best in Figure 7. In the cutting and forming of plate 4 to provide hinge barrels 19, tongue 17 can be readily formed from the same size plate. In the illustration given, tongue 17 is formed centrally on the rear edge of plate 4 between adjacent hinge barrels 19 by cutting slots 20 in plate 4, and then forming tongue 17 from the metal between hinge barrels 19. Slots 20 can be of any desired depth so long as they do not seriously weaken plate 4. Cutting slots 20 deeper will tend to increase the spring action of tongue 17, while using shallower slots will increase the rigidity or tension of tongue 17. However, I prefer to use relatively shallow slots, since shallow slots produce an adequate spring action in tongue 17 and do not weaken a mop-head plate composed of inexpensive steel.

It will be observed that tongue 17, as shown in Figure 7, projects outwardly from the raised central portion 11 of plate 4, and thus is slightly higher than the center of hinge 14. Thus, arcuate end portion 18 is easily made to frictionally engage the hinged edge of presser plate 13. The adjacent edge of presser plate 13, if desired, can be adapted to increase the frictional engagement with downwardly curved tongue portion 18. I have found it satisfactory, however, to simply cut a recess 21 in flanged portion 22 of presser plate 13, as shown best in Figure 2. If desired, the sides of recess 21 may be extended into flange 22 by means of slots 23. The cutting of slots 23 will assist in giving a spring action to the engaging edge 24 of flange 22. Also, if desired, the portion of flange 22 defined by slots 23 can be slightly raised, as shown in Figure 2.

The shape of tongue 17 and engaging edge 24 is susceptible to considerable modification without departing from the spirit of my invention. Edge 24 can be rounded to prevent undue scratching of the top of the raised portion of tongue 17, as shown in Figure 6. I prefer, however, to roll back edge 24 slightly as shown in Figures 3 and 4.

In Figure 6 arcuate portion 18 is modified by securing therein rivet 25. The purpose of rivet 25 is to positively lock edge 24 below rivet 25. It will be readily understood that in place of rivet 25 a bead or raised portion could be provided across the upper surface of arcuate portion 18.

I have discovered that the shape of the raised portion of tongue 17 can be modified as shown in Figures 3 and 4 so as to provide a latch which will hold lever 16 away from, but adjacent to handle 1. This result can be accomplished without the necessity for precise tolerances by providing arcuate portion 18 which has a downward concavity, with a flat or land portion 26 at the end of the arc. Flat portion 26 of tongue 17 is inclined upwardly to its integral connection with curved portion 18. As viewed from the side, the projecting end of tongue 17 has an S-shape, but the lower loop of the S is flattened to provide land 26.

As shown best in Figure 4, presser plate 13 is brought to a latched position by causing rounded edge 24 to move over the upper surface of curved portion 18 of tongue 17. Tongue 17 is allowed to yield downwardly as shown in Figure 4 during the latching of plate 13. When rounded edge 24 reaches the end of curved surface 18 and strikes the inclined land 26, the plate 13 is in latched position. At this point, considerable pressure is required to rotate plate 13.

either closer to or away from handle 1. Presser plate 13 is prevented from rotating downwardly because of its engagement with curved portion 18, and is prevented from moving toward handle 1 by the downward and forward inclination of flat portion 26.

Substantially this same result of locking plate 13 and lever 16 adjacent to but away from handle 1 can be accomplished by the modification shown in Figure 6, which has been previously described, or by providing an S-shape tongue projection. The particular advantage, however, of providing a flat inclined tongue portion beneath the arcuate tongue portion is that it is unnecessary to form the related flat and arcuate tongue portions to precise tolerances. This is true because the positive locking of plate 13 can occur over a range of positions, so long as plate 13 is held substantially upright and away from handle 1. In using a more exact engagement, as shown in Figure 6, it is necessary to form the parts more precisely.

It will be apparent that my latching means can equally well be used to secure lever arm 16 or presser plate 13 against handle 1 and socket 2 if this position is desired. I prefer, however, to secure lever 16 away from handle 1 and socket 2, since when these parts are touching it is very difficult to avoid some rattling of the adjacent metal surfaces.

In the illustration given, I provide spring 27 about hinge pin 15 of tongue 17. Spring 27 has arm extensions 28 on the ends thereof, which engage respectively the under surfaces of presser plate 13 and mop-head plate 4. Spring 27 is so formed that rotating plate 13 downwardly tightens spring 27. Thus, spring 27 is made to assist in returning plate 13 to its latched or upright position.

From the preceding description, it can be seen that my new latching device, in addition to its other advantages, provides a uniquely cooperative relationship with a mop of the structure illustrated in the drawing. Tongue 17 is readily formed from the same piece of metal as backing plate 4, and in reality is but a differently formed hinge barrel. Also, the engaged edge of presser plate 13 is readily adapted to form a latch with tongue 17, such as by slotting or rolling. Still further, the exposed portion of hinge pin 15 below arcuate tongue portion 18 provides an excellent location for spring 27.

While in the foregoing specification I have described in detail a specific embodiment of my latching device for purpose of illustration, it will be understood that numerous modifications can be made and will readily occur to those skilled in the art without departing from the spirit of my invention.

I claim:

1. In combination with a mop having an upwardly projecting handle secured to a mop-head including an elongated plate means having a presser plate means connected by an integrally formed hinge providing barrels to a longitudinal edge of the presser plate means, a resilient tongue projecting from said elongated plate means toward said presser plate means and being centrally located with respect to both said plate means, said tongue terminating in a raised end portion with a downward concavity extending between the barrels of said hinge to frictionally engage a rolled edge of said presser plate means to latch said presser plate means in an upright position and aligned with said handle, the rolled

edge of said presser plate means riding over the raised end portion of said tongue to a positive locking position on said tongue inwardly of said downward concavity.

5 2. In combination with a mop-head including an elongated mop-head plate having a presser plate, with a central rolled edge portion connected by a hinge to a rear edge of the mop-head plate, said hinge formed from alternating interlocking barrels integrally formed with said mop-head plate and said presser plate and having a centrally located spring poised against said hinged plates adjacent to said rolled edge so as to urge the presser plate to an upward position, a resilient tongue projecting from said mop-head plate toward said presser plate and terminating in an upwardly inclined end portion having a downward curvature, said end portion extending between the barrels of said hinge to frictionally engage the rolled edge of said presser plate to latch said presser plate, the rolled edge of said presser plate riding over the downwardly curved end portion of said tongue to inward position thereon by flexing said tongue downwardly.

10 3. In combination with a mop-head including a sponge-equipped plate means and a plate hingedly connected thereto for wringing said sponge, a resilient tongue projecting from said plate means toward the hinged edge of said wringing plate and having a raised end portion with a downward concavity and provided with a retaining recess below the concave portion adapted to provide a positive locking zone for an edge of said wringing plate, a portion of the hinged edge of said wringing plate riding over the raised end portion of said tongue to a position within said retaining recess by flexing said tongue downwardly, whereby said wringing plate can be held in an upright position.

15 4. In combination with a mop having an upwardly projecting handle secured to a mop-head including an elongated mop-head plate having a presser plate with a central lower rolled edge portion hingedly connected to a longitudinal edge of the mop-head plate, a resilient tongue projecting from said mop-head plate toward said presser plate and extending between hinge barrels provided by said longitudinal edge, said tongue terminating in a raised portion with a downward curvature connected by an upwardly inclined flat portion to a generally horizontal portion of said tongue to provide a positive lock for holding said presser plate in an upright position away from said handle a portion of the hinged edge of said presser plate riding over the downwardly curved portion of said tongue to a position on said upwardly inclined flat portion by flexing said tongue downwardly.

5. In combination with a mop having an upwardly projecting handle secured to a mop-head including an elongated mop-head plate having a presser plate hingedly connected along a longitudinal edge to a longitudinal edge of said mop-head plate, a resilient tongue projecting from said mop-head plate toward said presser plate and extending between hinge barrels provided by the longitudinal edge of said mop-head plate, said tongue terminating in a raised portion with a downward curvature and having a rounded projection near the point where said concave portion connects to a generally horizontal portion of said tongue, whereby there is provided a positive lock for holding said presser plate in an upright position away from said handle, a portion of the hinged edge of said presser plate

7
riding over the downwardly curved portion of said tongue and over said rounded projection to a position inwardly of said rounded projection by the downward flexing of said tongue.

6. In combination with a mop-head including an elongated plate means equipped with a sponge and having a presser plate hingedly connected along a longitudinal edge to a longitudinal edge of said sponge-equipped plate means, a resilient tongue projecting from said plate means towards the hinged edge of said presser plate and having a raised end portion with a downward concavity adapted to frictionally engage a portion of the hinged edge of said presser plate, the frictionally engaged portion of said presser plate hinged edge riding over the raised end portion of said tongue by flexing said tongue away from said presser plate, whereby said presser plate can be

5
positively locked in an elevated position by sliding the frictionally engaged portion of said presser plate to a position on said tongue inwardly of said downward concavity.

PHILIP K. O'CONNOR.
